UNITED STATES PATENT OFFICE.

JOHN W. DORRINGTON AND LEWIS G. FAY, OF WORCESTER, MASSACHUSETTS.

CURTAIN-HANGER.

SPECIFICATION forming part of Letters Patent No. 388,846, dated September 4, 1888.

Application filed March 23, 1887. Serial No. 232,173. (No model.)

To all whom it may concern:

Be it known that we, JOHN W. DORTINGTON and LEWIS G. FAY, citizens of the United States, residing at Worcester, in the county of Worcester and State of Massachusetts, have invented certain new and useful Improvements in Curtain-Hangers, of which the following is a specification, reference being had to the accompanying drawings, in which—

10 Figure 1 represents a front view of a portion of a window with our improved curtain-hanger attached thereto. Fig. 2 is a front view of the hanger detached from the window-casing. Fig. 3 is a rear view of the same. 15 Fig. 4 is an end view of the hanger applied to the window-casing and supporting a curtain-roll; and Fig. 5 is a sectional view on the line X X, Fig. 3.

Similar letters refer to similar parts in the several views.

Our invention relates to that class of curtain-hangers in which a bar is employed extending across the window from side to side and supporting the curtain-roll brackets, with connected means by which it is readily attached to or detached from the window-casing; and it consists in providing the curtain roll-supporting bar with one or more sliding bars, having brackets arranged to engage the edges of the window-casing and a spring whose tension is applied to hold the brackets firmly against the edges of the window-casing, in providing adjustable hooks to hold the curtain nearer the window, and in the arrangement and construction of the several parts, as hereinabove set forth in the description and specifically claimed in the claims.

In the drawings, A denotes the window-casing; B, the curtain-roll, held in the brackets B', attached to the supporting-bar C. (Shown in front and rear views in Figs. 2 and 3.) The bar C is recessed in its central section at D, forming a shallow rectangular pocket opening on the rear side of the bar to receive a flattened spiral spring, E. Extending in each direction centrally and lengthwise the bar are the T-shaped slots F F', in which are placed the sliding bars G G', with their outer ends turned up to form brackets G² G³ to engage the edges of the window-casing. Elastic bands H are drawn over the brackets with their outer sur-

faces corrugated to prevent marring the casing. The sliding bars G G' are provided with a series of holes, *a*, to allow the longitudinal adjustment of the sliding bars along the T-shaped slots F F'. The sliding bar G is held in position by a flat blade spring, I, attached by the screws *b b* to the bottom of the T-slot, and having its end bent at right angles and inserted in one of the holes *a* in the bar G.

Within the spiral spring E, we place a flat bar, J, having the pins c d, held in the bar J and against the ends of the spiral spring E. The end e of the bar J is bent at right angles and inserted in one of the holes a of the sliding bar G', thereby connecting the bars J and G, so a pressure against the side of the bracket G³ will cause the bar J to slide in the spring E and compress the spring. A pressure on the bracket G³ in the direction of the arrow 70 1 will press the pin e against the end of the spring E, causing a compression of the spring, as its opposite end is held by the wall forming the end of the recess D. A pressure on the side of the bracket G³ in the direction of 75 the arrow 2 will likewise press the pin d against the end of the spring and compress it in the opposite direction, the movement of the spring being resisted by the opposite end wall of the recess D. The tension of the spiral spring E will thus resist the movement of the connected bars J and G' in either direction.

The curtain-hanger is attached to a window-easing upon either the outer or inner edges of the casing, as desired. If upon the outer edges, as shown in the drawings, the bracket G^3 is placed over the edge of one side of the casing, as in Fig. 4, and the entire bar C pulled toward the opposite side of the window until the bracket G^2 can be hooked over the opposite outer edge of the casing, the pin d being drawn against the end of the spiral spring, causing the tension of the spring to be applied to draw the brackets G^2 G^3 firmly against the outer edges of window-easing, and the bar C held in any desired position to sustain the curtain-roll either at the extreme top of the window or at any distance below the top, as shown in Fig. 1, to allow the window to be opened at the top for the ventilation of the room.

In order to attach the curtain-hanger upon the inner edges of the casing, we place the bracket G^2 with its outer surface against the inner edge of one side of the casing and press the entire bar toward that side of the window until the bracket G^2 can be brought against the opposite inner side of the casing, the pin e being drawn against the end of the spiral spring, causing its tension to press the brackets $G^2 G^3$ firmly against the inner edges of the window-casing.

A metal bar, K , is carried over the edges and across the face of the bar C , and secured to the bar C by means of a spur, I , entering the upper edge of the bar C , and a set-screw, M , screwed against the lower edge of the bar C , permitting the metal bar K to be adjusted in its position along the curtain roll-supporting bar C .

20 A wire, N , is attached rigidly to the bar K and carried downward and outward a short distance below the bar C , and then bent inwardly in a horizontal position, as at P , Figs. 1 and 2, so as to extend over the edge of the curtain R , as shown in Fig. 1, the bent end P of the wire retaining the curtain nearer the window than it would otherwise hang by its own gravity. The opposite edge of the curtain is similarly held nearer the window by a bar, K' , having 30 a wire, I' , bent in an opposite direction. As curtains of different widths are used with the curtain-hanger, the bars $K K'$ are adjusted in their position on the bar C to correspond by means of their set screws $M M'$.

35 We are aware that a bar supporting a pair of curtain-brackets and having sliding bars sliding in ways in the curtain-supporting bar, and having brackets adapted to rest against either the outer or inner edges of the window-casing, have been before in use. Such we do 40 not claim. Neither do we claim herein the use of elastic bands upon the brackets to prevent the marring of the wood-work of the casing.

What we do claim as our invention, and desire to secure by Letters Patent, is—

45

1. In a curtain-hanger, the combination, with a bar having curtain supporting brackets and provided with a way for a sliding bar, of a bracket attached to said curtain-bracket-supporting bar and adapted to engage one of the sides of the window-casing, a bar sliding in a way in said curtain-bracket-supporting bar and having a bracket attached thereto adapted to engage the opposite side of the window-casing, and a spring held from lateral movement in said curtain-bracket-supporting bar with its tension applied to said sliding bar to draw its attached bracket firmly against the window-casing, substantially as described.

2. In a curtain-hanger, the combination, 60 with a bar having curtain-supporting brackets and a longitudinal way, of a pair of bars held in said way and capable of sliding in said way, brackets attached to said bars adapted to engage the sides of the window-casing, means, 65 substantially as described, by which the position of one of said bars is fixed in said way, and a spring held in said curtain-bracket-supporting bar with its tension applied to the opposite of said bars, substantially as described.

3. The combination, with a bar having curtain-supporting brackets and a bracket attached to said bar, but adjustable thereon, of a bar, G' , having a series of holes, a , a bar, J , adapted to engage said holes and having the 75 pins $c d$, and a spring, E , surrounding the bar J between the pins $c d$ and held in a pocket in the curtain-bracket-supporting bar, substantially as described.

JOHN W. DORRINGTON.
LEWIS G. FAY.
